UNITED STATES PATENT OFFICE.

LLEWELLYN A. GRIFFITH, OF BUFFALO, NEW YORK, ASSIGNOR TO GEORGE D. CAMPBELL AND ROBERT P. SMITH, OF BUFFALO, NEW YORK.

FOLDING CARRIAGE.

991,150.

Specification of Letters Patent.

Patented May 2, 1911.

Application filed December 28, 1909. Serial No. 535,272.

To all whom it may concern:

Be it known that I, LLEWELLYN A. GRIFFITH, a citizen of Canada, residing at Buffalo, in the county of Erie and State of New York, have invented new and useful Improvements in Folding Carriages, of which the following is a specification.

This invention relates to folding baby carriage or go-cart and has for its object 10 the production of a carriage of this character which is simple and durable in construction, which can be readily and easily folded and unfolded, which is very light and capable of being folded compactly, which 15 is very rigid and capable of supporting a considerable weight when unfolded for use, and which can be adjusted so that the child may either sit up or lie down.

In the accompanying drawings consisting 20 of 5 sheets:—Figure 1 is a side elevation of my improved folding carriage, showing the back and foot rest in one position. Fig. 2 is a vertical longitudinal section thereof showing the back and foot rest in another 25 position. Fig. 3 is a front elevation of the carriage. Fig. 4 is a top plan view of the same. Fig. 5 is a bottom plan view thereof. Fig. 6 is a front view showing the carriage folded. Fig. 7 is a side view thereof.

30 Similar letters of reference indicate corresponding parts throughout the several views.

In its general organization my improved baby carriage comprises a seat, A, a back 35 rest B arranged at the rear edge of the seat, a foot rest C arranged at the front edge of the seat, arm rests D arranged lengthwise on opposite sides of the seat, E the main handle for operating the carriage while in 40 use, and four supporting wheels F two of which are arranged at the front and two at the rear of the carriage.

The handle comprises two upright bars e 45 pivoted at their lower ends to opposite sides of the seat at the rear end thereof so as to swing vertically and lengthwise of the carriage, and a cross bar e¹ connecting the upper ends of the upright bars.

The back rest is pivoted at its lower edge 50 to opposite sides of the rear end of the seat so as to be capable of swinging vertically lengthwise of the carriage. The back rest may be adjusted so that it stands either upright, as shown in Fig. 1, for supporting the child in a sitting position, or that it in-

clines rearwardly, as shown in Figs. 2 and 4, for supporting the child in a lying position. The back rest is held in either of these positions by means of a holding device which is preferably constructed of wire in 60 the form of two side bars G each of which has a downward reverse bend or hook g at its front end which is pivoted by a rivet h or otherwise at its bill to the intermediate part of the adjacent handle side bar, a cross 65 bar g¹ connecting the rear ends of the side bars G in rear of the back rest, and stops or pins h¹ arranged at the side edges of the back rest below the side bars G. Upon swinging the holding bail downwardly 70 while the back rest is in its upright position and until the lower end of this bail engages the lower end of the seat on its rear side the reverse bends g of the same engage with the stops h¹, as shown in Fig. 1. While the 75 parts are in this position the back rest is reliably held in place inasmuch as any rearward pressure against the same is resisted by the bail which is pressed at its lower end forwardly against the back whenever the 80 stops of the back rest are pressed backwardly against the return bends of the bail, thereby holding the back rest reliably in its upright position. Upon raising the bail sufficient to permit the stops h¹ to swing rearwardly out of the return bends g the back 85 rest is free to swing rearwardly until the cross bar of the bail engages the rear side of the back rest, the downward movement of the bail at this time being arrested by the 90 stops h¹, thereby holding the backrest in an inclined position, as shown in Fig. 2.

Each of the arm rests is pivoted at its rear end to the outer side of one of the handle side bars and is pivotally connected at its 95 front end with the front end of the seat by a link I. When the carriage is unfolded the main handle and the links I both stand upright whereby the arm rests are raised in a horizontal position above the seat. Upon moving the main handle, links I and back rest forwardly into a position substantially parallel with the seat the arm rests are brought close to the seat and these parts are folded compactly, as shown in Fig. 7. 100 105

At its upper end the foot rest is pivoted on opposite sides by rivets j to the central parts of two vertically swinging links J which are pivoted at their upper ends on the front end of the seat while their lower ends 110

are connected by a transverse stop or bar j^1 which is arranged in rear of the foot rest. In rear of its pivots j the foot rest is provided with rearwardly projecting stops or 5 lugs k which are adapted to engage with the underside of the seat at the front end thereof.

When it is desired to place the child in a sitting position in the carriage the foot rest 10 is turned downwardly so that its stops are disengaged from the seat and the upper part of the foot rest below its pivots j bears against the stop j^1 of the links J , as shown in Figs. 1 and 3. When it is desired to hold 15 the foot rest in a horizontal position so that the child may lie down, this is effected by swinging the foot rest up and engaging its stops k with the underside of the seat, as shown in Figs. 2 and 4.

20 L , L^1 represent the front and rear transverse axles of the carriage on opposite ends of each of which a pair of the supporting wheels is pivotally mounted. The front axle is pivotally connected with the seat by a 25 pair of folding bars M each of which is pivoted at its lower end to one end of the front axle while its upper end is pivoted to one side of the seat at the rear end thereof.

M^1 represents a pair of forwardly inclined folding bars each of which is pivoted at its lower end to one end of the rear axle while its central part is pivotally connected by a rivet m or otherwise with the central part of the adjacent folding bar M .

35 N , N^1 represent a pair of guide bars which control the movement of the folding bars M^1 and each of which is pivotally connected at its front and rear ends, respectively, with the upper end of one of the folding bars M^1 40 and with one of the handle side bars while its intermediate part slides in a swivel or guide loop n which is pivoted on the adjacent side of the seat adjacent to the front end thereof.

45 In the unfolded position of the cart, as shown in Figs. 1 and 2, the two folding bars on each side of the carriage are substantially at right angles to each other and the guide bar is moved rearwardly in the guide 50 loop n , so that it is arranged at a considerable angle relatively to the seat. Upon folding the main handle and the back forwardly over the seat the guide bars N slide forwardly through the loop n and the folding 55 bars turn upon each other until these bars are substantially parallel with the seat and lie close together, as shown in Fig. 7, whereby the carriage is rendered compact for storage or transportation. While thus folding 60 the seat, back rest, main handle, guide bars and folding bars, the foot rest projects forwardly from the seat so that it lies parallel with the seat and back rest in the folded position of the parts and produces a compact arrangement.

For the purpose of stiffening the structure the corresponding folding bars on opposite sides of the carriage may be connected by braces, such as a connection o being shown 70 between the folding bars M^1 .

The carriage is held in its unfolded position by a retaining device which preferably consists of a longitudinal spring bar o^1 secured at its rear end centrally to the rear axle and provided at its front end with a catch o^2 which is adapted to engage with the front side of the front axle and prevent the axles from spreading while the carriage 75 is in use.

The supporting wheels are mounted on the axles so that they may be shifted into an operative or unfolded position at right angles to the axles or into a folded or inoperative position parallel with the axles. The preferred means whereby each wheel is 80 thus mounted on one end of an axle comprises a shifting rock lever P pivoted at its inner end to the underside of an axle by a vertical rivet p or other means, so that this lever is capable of swinging horizontally. An elbow lever is pivoted by a horizontal longitudinal pivot q to the outer end of the shifting lever P and has an upper horizontally outward projecting arm q^1 on which 85

90 one of the supporting wheels is journaled and a lower vertical downwardly projecting arm q^2 . A shifting link R is arranged parallel with the axle and connected at its outer end by a horizontal pivot r with the lower arm q^2 of the elbow lever while its inner end is connected by a vertical pivot r^1 with a lug r^2 arranged on the outer side of the adjacent part of the axle and forming a part 95 thereof. Two diagonal shifting rods s , s^1 100 are provided which cross each other between the front and rear axles and each of which is pivotally connected at its front end with the central part of the shifting lever P on one end of the front axle while its rear end is pivotally connected with the central part 105 of the shifting lever P on the opposite end of the rear axle. By means of this mechanism the movement of the axles to the position in which they approach each other most closely in unfolding the carriage causes the shifting rods s to turn the shifting levers P outwardly parallel with the axles and the shifting links R to turn the elbow levers so 110 that the wheels stand upright and at right angles to the axles, as shown in Figs. 1-5. Upon moving the axles away from each other for folding the carriage the shifting rod s turns the shifting levers P inwardly 115 at an angle to the axles and the links R turn the elbow levers so that the lower arms thereof are parallel with the axles and shifting levers P , thereby causing the wheels to 120 swing inwardly close to the underside of the seat and in a position parallel thereto, 125 as shown in Figs. 6 and 7. In the unfolded 130

position of the shifting levers the same engage by stops *t* thereon with the inner sides of the axles, thereby stiffening the carriage while in use.

- 5 The folding and unfolding movements of the handle, back rest, seat, wheels and associated parts are effected in unison and with but one operation owing to the connection between these parts which compels them to 10 move simultaneously, thereby permitting the operation of getting the carriage ready for use or for storage to be effected expeditiously and conveniently.

For convenience in carrying the carriage 15 when the same is in its folded condition a supplemental handle *u* is provided which is preferably secured to the front axle. This handle together with the main handle *E* also permits readily operating the parts for 20 folding or unfolding the carriage.

Upon unfolding the carriage the catch *o²* engages automatically with the front axle this being permitted by providing the front end of this catch with a beveled face where- 25 by the same can trip over this axle. Before folding or collapsing the carriage the catch *o²* is released by hand from the front axle to permit the axles to separate and the other parts be moved into their folded position.

30 I claim as my invention:

1. A folding carriage comprising a seat, a handle pivoted to the rear of said seat, a pair of front and rear axles arranged below the seat, wheels supported by said axles, a 35 pair of folding bars each pivoted at its lower end to one end of the front axle and at its rear end to the rear end of the seat, another pair of folding bars each pivoted at its lower

end to one end of the rear axle while its central part is pivotally connected with the 40 central part of the adjacent folding bar of the first mentioned pair, a pair of guide bars each pivoted at its rear end to the adjacent side of said handle while its front end is pivotally connected with the upper end of the 45 adjacent folding bar of the last mentioned pair, and a pair of swivels each arranged on one side of the seat and having a sliding connection with the adjacent guide bar.

2. A folding carriage comprising a seat, 50 two axles arranged below the seat and movable toward and from each other, shifting levers pivoted on the opposite ends of each axle, elbow levers each pivoted on one of said shifting levers, and wheels mounted on 55 said elbow levers.

3. A folding carriage comprising a seat, two axles arranged below the seat and movable toward and from each other, shifting levers pivoted on the opposite ends of each 60 axle, an elbow lever pivoted on each shifting lever and having an upper arm and a lower arm, wheels journaled on the upper arms of the elbow levers, links pivotally connecting the lower arms of the elbow levers with the 65 axles and diagonal shifting rods which cross each other and each of which is pivotally connected at opposite ends with a shifting lever at one end of one axle and a shifting lever at the opposite end of the other axle. 70

Witness my hand this 21st day of December, 1909.
